[57] CLAIM

The ornamental design for a water ski, substantially as shown and described.

DESCRIPTION

FIG. 1 is a top plan view of a water ski showing my new design;

FIG. 2 is a right side view thereof, the left side being a mirror image thereof;

FIG. 3 is a bottom view thereof;

FIG. 4 is an enlarged front view thereof;

FIG. 5 is an enlarged rear view thereof;

FIG. 6 is an enlarged sectional view taken along the line
6—6 thereof; and

FIG. 7 is an enlarged sectional view taken along the line
7—7 thereof.

The drawing is lined for the colors blue and green. No claim is made to any particular color.
